(57) **CLAIM**

The ornamental design for a blender, as shown and described.

DESCRIPTION

Figure 1.1 is a front axonometric view of a blender showing my new design;

Figure 1.2 is a front elevational view thereof;

Figure 1.3 is a rear elevational view thereof;

Figure 1.4 is a left side elevational view thereof;

Figure 1.5 is a right side elevational view thereof;

Figure 1.6 is a top plan view thereof; and

Figure 1.7 is a bottom plan view thereof.

The broken line showing of a blender base depicts environment and forms no part of the claim.
